CRANKSHAFT TRUING TOOL

Jerome L. Tindall and Willie M. Patrick,
Amarillo, Tex.

Application July 22, 1936, Serial No. 92,040

10 Claims. (Cl. 82—4)

The invention provides a tool of novel and peculiar construction designed for truing or reconditioning crank shafts, and particularly for truing crank pins of internal combustion engines and analogous bearing members to eliminate flat places and tapered conditions and thus provide a perfectly cylindrical surface to assure smooth running and even wear. The tool may be used on said parts while they are still in the engine or it 10 may be used in combination with a lathe.

Heretofore tools have been proposed for turning or truing crank shafts or crank pins, but these were constructed more in the shape of long wrenches which prevented their use on the crank 15 shaft in the engine and therefore necessitated the removal of the crank shaft in order to operate on the crank pins thereof. Such tools as have been proposed of substantially symmetrical form were not constructed capable of being applied to the 20 crank shaft in place in the engine.

The object of this invention is to provide a tool of the character specified in which the operating elements may be held in a circular, or other symmetrical form, and which tool is so constructed 25 that it may be readily attached to or removed from the crank shaft of an internal combustion engine without necessitating removal of the crank shaft from the engine or the removal of associated parts, particularly the connecting rod and 30 piston, and the subsequent replacement thereof.

The invention provides a tool that is adjustable within certain limits to fit shafts or other work of different sizes and to properly center the work therein and the essential elements of which tool 35 are held in proportional and operative relationship to each other.

While the drawing illustrates a preferred embodiment of the invention, it is to be understood that in adapting the same to meet specific needs 40 and requirements, the design may be varied and changes in the minor details of construction may be resorted to within the scope of the invention as claimed, without departing from the spirit thereof.

For a full understanding of the invention and the merits thereof, reference is to be had to the following description and the drawing hereto attached, in which:

Figure 1 is a side view of an embodiment of 50 the invention showing it applied to the crank shaft of an engine, the cylinder block of which is shown in section and the cylinder containing a piston which is disconnected from the crank shaft.

Figure 2 is an enlarged perspective view of the 55 tool.

Figure 3 is a detail sectional view on the line 3—3 of Figure 2, looking in the direction of the arrows.

The tool is constructed with a body 4 which is symmetrical in outline, preferably circular, which body 4 is preferably constructed rigidly in one piece. The body 4 has a radially extending opening 15 in one side thereof constituting a throat, which throat is provided with parallel sides extending inwardly from the periphery of the body 10 4, at least to the center thereof and having an arcuate inner end. The sides of the throat are spaced apart sufficiently far to enable the tool to be slipped over a crank pin or other work, designated generally by the numeral 17 in Fig. 1, to 15 which it is adapted, so the work may be centered with respect to the body 4 for proper turning of the body thereon during operation of the tool to provide a circular outline therefor in truing the work to the proper shape. Radial openings 16 20 are spaced at intervals around the periphery of the body 4 to receive a rod 21 which may be inserted therein for rotating the tool about the crank pin 17.

A centering rest 5 is mounted in the body 4 at 25 one side of the throat 15 and on the opposite side thereof is a holding rest 7, arranged substantially in alignment with the centering rest 5. Each of the rests 5 and 7 is formed of substantially 30 U-shape, as shown in Fig. 3, having the sides thereof slidably mounted in radially recessed grooves 25 in opposite sides of the body 4, while the rest is locked in place by one or more locking screws 20, extending through slots 19 in the body 4 and engaging the opposite sides of the rest to 35 draw the same inwardly into binding relation with the sides of the body 4 to hold the rest in the desired adjusted position, as shown at the bottom of Fig. 3. Adjusting screws 8 and 10 extend radially in the body 4 and bear at their inner ends 40 against the rests 5 and 7, respectively, to adjust the rests radially with respect to the body 4, to accommodate work of different sizes and to hold the work or crank pin in the proper position and properly centered in the body 4. A scale 18 is provided on the body 4 adjacent an edge of the rest 5 to cooperate with an indication on the rest 5 for indicating the degree of adjustment of the rest, making it possible to locate the centering rest in the desired position with respect to the body 4, 50 according to the character of work on which the tool is to be operated.

Mounted on the same side of the throat 15 as the holding rest 7 is a blade holder 6, which is likewise of U-shape with the sides thereof 55

slidably mounted in radially recessed grooves 25a, in the sides of the body 4, being adjustable by a screw 9, mounted similar to the screws 8 and 10, and the blade holder 6 is locked in place 5 by means of a locking screw 20a, extending through a slot 19a in the body 4. The inner end of the blade holder 6 has a substantially wedge shaped groove therein receiving a cutting blade or working tool 11, which is locked in place 10 by a block 12 secured by set screws to the inner end of the blade holder 6.

The inner end of the centering rest 5 is constructed with sides or work engaging faces 13 and 13a, arranged in substantially V-shape adjacent 15 the inner end of the throat 15 to receive and properly center the work or crank pin with respect to the body 4. The inner end of the holding rest 7 has a face 14 between its oppositely inclined edges to engage the work on 20 the opposite side thereof from the V-shaped faces 13 and 13a and cooperating therewith to hold the tool in proper rotatable relation with respect to the work. The faces 13, 13a and 14 are hardened to resist wear by contact with the 25 work.

The parts are so arranged that the working tool or blade 11 lies in a plane extending radially through the center of the crank pin 17, and perpendicular to the face 13a, approximately 30 midway of the length of said face, which relation enables the tool to turn the crank pin, bearing or other work to a true cylindrical form as desired. The adjustment of the centering rest, holding rest, and blade holder radially with 35 respect to the body 4, properly centers the tool on the work to obtain this cylindrical form of the work. The blade or working tool 11 may be adjusted by screws 22 which extend substantially lengthwise of the blade holder 6 at each 40 side thereof, to bring its cutting edge into parallel relation ship with the faces 13 and 13a of the V-shaped centering rest.

It will be evident that the holding rest 7 should be retracted in the throat 15 to permit the tool to 45 be applied to the crank pin or other work. The adjustment of the centering rest 5 having been made for application of the tool to the crank pin, according to the size of the crank pin on which the tool is to be used, the tool is slipped thereover until the V-shaped centering rest fits 50 properly on the crank pin, after which the holding rest is adjusted by the screw 10 into relatively close contact with the opposite side of the crank pin to hold the tool firmly but rotatably thereon. If proper adjustments have previously 55 been made, the edge of the cutting tool 11 will be in proper operating relation to the periphery of the crank pin for truing the same upon rotation of the tool thereon, shaping the 60 crank pin to a true cylindrical form. After the tool is properly fitted to the crank pin or other work, it is rotated intermittently by the rod 21, being engaged in the respective openings 16 in the periphery of the tool, the rod being shifted 65 from one opening to another between stages of rotation, and this operation continued until the crank pin is shaped and trued as desired, after which the tool may be removed by withdrawal of the holding rest 7.

70 It will be evident that the use and operation of this tool does not require the removal of the crank shaft from the engine, but it is only necessary to disconnect the connecting rod and move the piston into the upper portion of the cylinder 75 in the cylinder block 23, as shown in Fig. 1, thus

effecting a substantial saving of time and labor in performing this operation.

It will be understood that the tool is of such construction that it may be fitted to a crank-shaft or other part to be trued without necessitating the removal of such part from the engine in which it is mounted, or it may be used in combination with a lathe in this form or a variation thereof. The rests and cutter are each independently adjusted by the coacting adjusting screws in the manner stated. It is to be further noted that cutter 11 immediately follows rest 7, this allows adjustment of blade within close limits and allows uniform cutting without digging in or chattering. Due to the cutter 11 being closely spaced to the rear of rest 7, springiness is eliminated and a uniform cutting is obtained. Again it is to be noted that by adjustment of rest 5 and cutter blade 11, the surface 13a and the cutter blade 11 have their 15 points of contact on the shaft diametrically opposite each other, thus determining the diameter of the shaft to be trued. The rest 7 holds the work firmly yet rotatably within the V of the centering rest 5, thus allowing a free and 20 independent adjustment of cutter 11.

Having thus described the invention, what we claim is:

1. A tool of the character described comprising a unitary rigid symmetrical body of approximately uniform radius throughout, said body having an open work-receiving throat in a side thereof and extending approximately to the center of said body, a working tool in a side of said throat, and means adjacent said working tool for holding the work, said body having means spaced at intervals around the periphery thereof for turning the body. 30

2. A tool of the character described comprising a unitary rigid symmetrical body of approximately uniform radius throughout, said body having a work-receiving throat in a side thereof and extending approximately to the center of said body, a working tool, means for holding the work adjacent said working tool, including a V-shaped centering rest mounted at a side of the throat, and a holding rest slidable radially of the body into the throat between the outer end thereof and the work. 40

3. A tool of the character described comprising a unitary rigid symmetrical body of approximately uniform radius throughout, said body having an open work-receiving throat in a side thereof and extending approximately to the center of said body, a working tool, means for holding the work adjacent said working tool, including a V-shaped centering rest mounted at a side of the throat, and a holding rest slidable radially of the body into the throat between the outer end thereof and the work, the working 50 tool being arranged in a plane passing approximately through the center of the work in the holding means and intersecting one of the faces of the V-shaped centering rest. 55

4. A tool of the character described comprising a unitary rigid symmetrical body of approximately uniform radius throughout, said body having an open work-receiving throat in a side thereof and extending approximately to the center of said body, a working tool, means for holding the work adjacent said working tool, including a V-shaped centering rest mounted at a side of the throat, and a holding rest slidable radially of the body into the throat between the outer end thereof and the work, the working tool 60

being arranged in a plane passing approximately through the center of the work in the holding means and intersecting one of the faces of the V-shaped centering rest approximately perpendicular thereto.

- 5 5. A tool of the character described comprising a body having a rigid V-shaped centering rest, means for adjusting said rest bodily relative to the body, a holding rest carried by the body and 10 cooperating with the centering rest to hold work therein, and a working tool carried by the body, the plane of said working tool passing approximately through the center of the work in the rests and intersecting one of the faces of the 15 V-shaped centering rest approximately perpendicular thereto.

6. A tool of the character described comprising a body having a rigid V-shaped centering rest, means for adjusting said rest bodily relative to 20 the body, a holding rest carried by the body and cooperating with the centering rest to hold work therein, a working tool carried by the body, the plane of said working tool passing approximately through the center of the work in the rests 25 and intersecting one of the faces of the V-shaped centering rest approximately perpendicular thereto, and means for adjusting said working tool and holding rest independently relative to the centering rest.

- 30 7. A tool of the character described comprising a unitary rigid symmetrical body of approximately circular outline and having a permanently open work-receiving throat in a side thereof and extending to the center of said body, means for holding work approximately at the center of 35 said body, and a working tool mounted in said body in a side of said throat adjacent the center thereof, said body having orifices spaced at intervals around the periphery thereof to receive 40 operating means therefor.

8. In a tool of the character specified, a sym-

metrical body having a throat with an open outer end, a radially adjustable V-shaped centering rest mounted at a side of the throat, a radially adjustable holding rest mounted in a side of the throat approximately opposite said V-shaped centering rest, a radially adjustable cutting tool mounted approximately perpendicular to one of the faces of the V-shaped centering rest, and means for rotating the tool.

9. A tool of the character described comprising 10 a unitary rigid symmetrical body of approximately uniform radius throughout, said body having a work-receiving throat in a side thereof and extending approximately to the center of said body, a working tool in a side of said throat, 15 means for holding the work approximately at the center of the body, work holding means between said working tool and the outer end of the throat, said work holding means being slideable approximately radially of the body into the throat between the outer end thereof and the work.

10. A tool of the character described comprising a unitary rigid symmetrical body of approximately uniform radius throughout, said body having a work receiving throat in a side thereof 25 and extending approximately to the center of said body, a working tool in a side of said throat, means for holding the work approximately at the center of the body and adjacent said working tool, adjustable work holding means slideable radially of the body in the throat between the outer ends thereof immediately forward and adjacent said working tool, said work holding tool being approximately diametrically opposite the first-mentioned work holding means, and said 30 working tool being approximately diametrically opposite one of the contact faces of said adjustable centering means.
